ATTORNEY

UNITED STATES PATENT OFFICE.

EVERETT K. JENKINS, OF OVERBROOK, PENNSYLVANIA.

DESIGN FOR A BASKET.

49,776.

Specification for Design.

Patented Oct. 17, 1916.

Application filed July 17, 1916. Serial No. 109,840. Term of patent 7 years.

To all whom it may concern:

Be it known that I, EVERETT K. JENKINS, a citizen of the United States, residing at Overbrook, in the county of Philadelphia and State of Pennsylvania, have invented a new, original, and ornamental Design for a Basket, of which the following is a specification, reference being had to the accompanying drawing, forming part thereof.

Figure 1 is a perspective view of a basket.

Fig. 2 is an end view of the basket, showing my new design.

I claim:

The ornamental design for a basket, as shown.

EVERETT K. JENKINS.
